UNITED STATES PATENT OFFICE

EMIL A. MULLER, OF NEW YORK, N. Y.

DESIGN FOR AN ELECTRICAL ATTACHMENT PLUG HANDLE CAP

Application filed June 5, 1929. Serial No. 31,551. Term of patent 14 years.

To all whom it may concern:

Be it known that I, EMIL A. MULLER, a citizen of the United States, and a resident of the city of New York, borough of Queens, and State of New York, have invented a new, original, and ornamental Design for Electrical Attachment Plug Handle Cap, of which the following is a specification, reference being had to the accompanying drawing, forming part thereof, wherein:—

Fig. 1 is an elevation of my new design;

Fig. 2 is a plan thereof, and

Fig. 3 is an elevation of the device rotated through an angle of 45° relative to Fig. 1.

I claim:

The ornamental design for an electrical attachment plug handle cap, as shown.

EMIL A. MULLER.
